UNITED STATES PATENT OFFICE

162,119

BEDSIDE TABLE

Harry M. Berner, Chicago, Ill., assignor to American Hospital Supply Corporation, Evanston, Ill., a corporation of Illinois

Application February 11, 1949, Serial No. 804

Term of patent 14 years

(Cl. D33—14)

To all whom it may concern:

Be it known that I, Harry M. Berner, a citizen of the United States, residing at Chicago, county of Cook, and State of Illinois, have invented a new, original, and ornamental Design for a Bedside Table, of which the following is a specification, reference being had to the accompanying drawing forming a part thereof, in which:

Figure 1 is a perspective view of a bedside table, showing my new design; Fig. 2, a top plan view; Fig. 3, a side view in elevation; Fig. 4, a front view in elevation; and Fig. 5, a bottom plan view of the table top.

I claim:

The ornamental design for a bedside table, as shown.

HARRY M. BERNER.
